UNITED STATES PATENT OFFICE.

J LINUS HELSING, OF DES MOINES, IOWA.

COLLAPSIBLE WEDGE BLOCK.

Application filed June 9, 1927. Serial No. 197,737.

The purpose of my invention is to provide a collapsible wedge structure particularly adapted for use in connection with mine props.

5 It is a special purpose of my invention to provide a pair of supporting members or blocks, one or both of them having the form of a wedge and to provide means for connecting them against sliding movement with 10 relation to each other, while they are used for supporting props, said means being such as to permit its movement to inoperative position, when it is desired to remove the props, for thus permitting one of said members to 15 slide with relation to the other.

With these and other objects in view, my invention consists in the construction, arrangement and combination of the various parts of my collapsible wedge, whereby the 20 objects contemplated are attained, as hereinafter more fully set forth, pointed out in my claims, and illustrated in the accompanying drawings, in which:

Figure 1 is a side elevation of a collapsible 25 wedge embodying my invention installed in connection with a mine prop.

Figure 2 is a perspective view of the lower block forming a part of my collapsible wedge structure.

30 Figure 3 is a perspective view of the lower block of a slightly modified form of my device.

Figure 4 is a vertical, sectional view 35 through my collapsible wedge structure, embodying the modified form.

Figure 5 is a perspective view of the operating screw used with the modified form.

Figure 6 is a perspective view of the small adjustable wedge used in the modified form.

40 Figure 7 is a vertical, sectional view of the wedge shown in Figure 6 taken on the line 7-7 of Figure 6.

Figure 8 is a horizontal, sectional view taken on the line 8-8 of Figure 7; and

45 Figure 9 is a perspective view of the rod used with my device.

It is well known that in coal and other mining, it is common practice to use props for supporting the roof. For convenience in explaining the structure and use of my collapsible wedge structure, I will refer to it as it is used in coal mines.

50 In mining coal, wherever it is necessary to support the roof, it is found that the cost of props makes a very considerable item of expense.

Heretofore it has not generally been the practice to remove the props after they were installed, because the difficulty of such removal made the expense too great.

60

It is my purpose to provide a device which can be used for installing the props and which will permit the convenient, quick and easy removal of the props.

In coal mining in some sections of the 65 country, it has now become common practice to mine along a long face instead of in rooms. The roof is supported by props, and as the mining operations advance, the rear props may be removed and the roof allowed to drop.

70

Heretofore the removal of the props has been so expensive as to be prohibitive. With my device, the props can be removed at a very moderate expense and used repeatedly.

In Figure 1, I have illustrated the manner 75 in which my device can be used.

A plate or block or the like indicated by the reference numeral 10 is placed on the mine floor. My collapsible wedge structure comprising the blocks 12 and 14 is supported on 80 the block 10. On my collapsible wedge structure, I place an ordinary prop 16 in upright position. On the upper end of the prop 16 may be placed a block or cap 12.

After the prop has served its purpose for a 85 sufficient length of time, my collapsible wedge structure is released and the prop may be taken out and used elsewhere.

My improved collapsible wedge structure is shown in one form in Figures 1 and 2 and 90 in another form in Figures 3 to 8 inclusive.

I install in the form shown in Figures 1 and 2, the blocks 12 and 14. The block 12 has a flat bottom and an inclined upper face 20. The face 20 is inclined from what I will for 95 convenience call the rear face 12^a of the block 12 downwardly and forwardly from the horizontal.

I have for convenience indicated the end 100 faces of the block 12 by the numerals 12^b and 12^c.

The upper inclined face 20 of the block 12 is provided with a longitudinal groove 22. The front face of the groove 22 indicated at 105 22^a is arranged in a plane at right angles to the plane of the face 20.

The groove 22 is deep enough to wholly receive a heavy rod 24, preferably of steel.

For coacting with the block 12, I preferably 110 provide the block 14, having the upper face 14^a, which is in a horizontal plane when the device is completely assembled.

The under-face of the block 14 indicated at 26 is beveled to correspond to the bevel of the face 20 and is provided with a longitudinal groove 28 of such depth as to receive somewhat less than half of the cylindrical rod 24.

In the use of my collapsible wedge structure, the block 12 is placed on the base 10 in the proper location. I then partially fill the groove 22 with sand 30. The sand 30 is filled 10 to such a height as to support the rod 24 in position for projecting above the face 20 sufficiently to substantially and snugly fill the groove 28.

The block 14 is then placed in position 15 where the groove 28 receives the rod 24.

The prop 16 is set on the block 14 and the cap 18 inserted snugly under the mine roof. If the roof sags any, it rests on the structure thus erected and will be held against falling.

20 After the prop has served its purpose, I drill out a portion of the sand 30. It will be understood that removable gates 30^a, held in place by guides 30^b, are used to hold the sand in place at the ends of the groove 22 until the 25 time for removal arrives. After a portion of the sand 30 has been taken out in any convenient way, the block 12 may be tapped, whereupon the sand will drop, thus permitting the rod 24 to drop, whereupon the block 14 will slide down the face 20 and the supporting structure will be collapsed. The blocks 30 12 and 14 are preferably of cast metal but may be of any suitable material.

In Figures 3 to 8 inclusive, I have shown 35 a slightly different form in which my collapsible wedge block can be embodied.

In this modified form, I use a block 32 similar to the block 12 provided with the groove 34 similar to the groove 22.

40 Midway of the groove 34, I provide an offset recess 36 extending toward the rear wall of the face 32^a of the block 32. A threaded hole 38 extends from the lower part of the recess 36 to the face 32^a. A screw 40 is 45 threaded into the hole 38. The screw 40 has the outer head 40^a, and at its inner end the reduced neck 40^b and the enlarged head 40^c.

Slidable in the recess 36 and groove 34, I provide a small wedge or block 42, having 50 the forward beveled face 42^a. In the lower rear, central part of the wedge 42 is a slot 44, which at its inner end has an enlarged portion 46. The slot 44 is intended to receive the reduced neck 40^b of the screw 40 and the 55 enlarged portion of the slot as at 46 receives the head 40^c rotatably.

In the modified form of my device, the block 14 is the same as that shown in Figure 1.

60 In installing the parts for use, the block 32 is placed on the base 10 in the manner already described.

The screw 40 is rotated for forcing the 65 small wedge 42 to its forward limit of movement, where it projects into the groove 34

as shown in Figure 4. The rod 24 is then dropped into place in the groove 34 resting on the upper part of the beveled face 42^a.

The block 14 is placed in position with less than half of the rod 24 projecting into the 70 groove 28.

The prop may be installed in the usual way.

After the prop has served its purpose, the screw 40 may be manipulated for pulling the 75 small wedge 42 into the recess 36 and permitting the beveled face of the block 14 to slide down the upper beveled face of the block 32.

It will be seen that when the parts are installed as shown in Figure 4 for holding the 80 prop 16 in place, the block 14 will tend to force the rod 24 against the right-hand face 34^a of the slot 34, which lies in a plane at right angles to that of the top face of the block 32, and that there is very little downward pressure on the rod 24. There is enough tendency, however, to force the rod 24 downwardly, so that when the small wedge 42 is removed, the rod 24 will drop down. 85

With a device of this kind, a very great saving can be effected in mines. Props can be used over and over again, and they can be removed from the place of installation quickly and cheaply enough to make the removal profitable. 90

It will be understood that I do not by my present claims intend to limit myself to any particular details of construction or kinds of material, and that it is my purpose to 100 cover by my claims any modified forms of structure or use of mechanical equivalents, which may be reasonably included within the scope of my claims.

I claim as my invention:

1. In a wedge block structure of the class described, a pair of blocks having respectively a horizontal lower and a horizontal upper face and having adjacent beveled faces inclined from the horizontal, said blocks having in their adjacent faces registering horizontal recesses, a cylindrical member received in said recesses, and movable means for holding said cylindrical member in raised position, the recess in the lower block being of sufficient depth to permit the cylindrical member to drop downwardly thereinto when the movable means is removed from such recess. 105

2. In a device of the class described, a pair of blocks having respectively a lower horizontal and an upper horizontal face and having adjacent beveled faces, said blocks having in said beveled faces registering horizontal recesses, an adjustable round faced member adapted to be partially received in the respective recesses in said blocks, means for holding said last-mentioned member in raised position adapted to be moved to position for permitting said adjustable mem- 120
125
130

ber to drop into the recess in the lower block to thus permit the upper block to slide freely from the lower block.

3. In a device of the class described, a pair of blocks having respectively lower and upper horizontal faces and having adjacent beveled faces, one block being superposed upon the other, said blocks having in their adjacent faces horizontal registering grooves, a cylindrical rod received in said grooves, the lower face of the groove in the lower block being arranged in a plane substantially at right angles to that of the beveled face of said block, and movable means for holding said cylindrical member in raised position with less than half of its bulk projected into the groove in the upper block.

4. In a device of the class described, a pair of blocks having respectively lower and upper horizontal faces and having adjacent beveled faces, one block being superposed upon the other, said blocks having in their adjacent faces horizontal registering grooves, a cylindrical rod received in said grooves, the lower face of the groove in the lower block being arranged in a plane substantially at right angles to that of the beveled face of said block, and movable means for holding said cylindrical member in raised position with less than half of its bulk projected into the groove in the upper block, said means comprising a slideable wedge, and means for adjusting said wedge to different positions for holding said movable member up or permitting it to drop into the groove in the lower block.

5. In a device of the class described, a pair of blocks having coacting adjacent beveled faces, said faces being provided with horizontal, transverse recesses adapted to register with each other when one of the blocks is superposed above the other, a member having a rounded upper face received in the recess in the lower block and capable of vertical up and down movement partially into and entirely out of the recess in the upper block, and means for controlling the up and down movement of said member.

6. In a device of the class described, a pair of blocks having coacting adjacent beveled faces, said faces being provided with transverse recesses adapted to register when one block is superposed upon the other, the recess in the lower block having its lower side wall portion arranged in a plane substantially at right angles to that of the beveled face of the lower block, a member adapted to travel into and out of the recess in the lower block along said face in an up and down movement, and means for controlling such movement of said member.

7. In a device of the class described, a pair of blocks having respectively lower and

upper horizontal faces and having adjacent beveled faces, said blocks having in their adjacent faces transverse horizontal recesses adapted to register when the upper block is superposed upon the other block, a substantially cylindrical member received in the recess in the lower block and adapted to be projected into the recess in the upper block, and movable means for holding said cylindrical member in raised position partially projected into the recess in the upper block adapted to be moved to position for permitting the cylindrical member to move downwardly bodily into the recess in the lower block.

8. In a device of the class described, a pair of blocks, one of which is adapted to be superposed upon the other, the adjacent faces of the block having transverse recesses adapted to register when one block is thus superposed upon the other, a member adapted to travel up and down in said recesses having a face in the form of a part of a cylinder, the recess in the upper block having a face of corresponding shape, and means for controlling the up and down movement of said member.

9. In a device of the class described, a pair of blocks having coacting adjacent beveled faces, said faces being provided with horizontal transverse recesses adapted to register with each other when one of the blocks is superposed on the other, a locking member having a rounded upper face received in the recess in the lower block and capable of substantially vertical up and down movement partially into and entirely out of the recess in the upper block, and means for supporting such member in raised position partially projected into the upper block and adapted to be moved away from such supporting position.

10. In a device of the class described, a pair of blocks having coacting adjacent beveled faces, said faces being provided with transverse recesses adapted to register when one block is superposed upon the other, the recess in the lower block having its lower side wall arranged in a plane substantially at right angles to that of the beveled upper face of the lower block, a cylindrical member received in the lower transverse recess capable of movement upward to project for less than half its bulk into the upper recess, and means for holding the member raised capable of movement to inoperative position, said parts being so arranged that when said member is raised and said means is in inoperative position the upper block will force said member down so that the upper block may slide off the lower block.

Des Moines, Iowa, May 28, 1927.
J LINUS HELSING.
